UNITED STATES PATENT OFFICE.

ERNEST W. PRIGAN, OF AKRON, OHIO, ASSIGNOR OF ONE-FOURTH TO GEORGE T. SMITH, OF AKRON, OHIO, ONE-FOURTH TO FRANK M. KIRK, OF CLEVELAND, OHIO, AND ONE-FOURTH TO L. E. FISCHMAN, OF AKRON, OHIO.

ROTARY ENGINE.

1,230,923.

Specification of Letters Patent. Patented June 26, 1917.

Application filed July 2, 1913. Serial No. 777,048.

To all whom it may concern:

Be it known that I, ERNEST W. PRIGAN, a citizen of the United States, and a resident of Akron, county of Summit, and State of Ohio, have invented a new and useful Improvement in Rotary Engines, of which the following is a specification, the principle of the invention being herein explained and the best mode in which I have contemplated applying that principle, so as to distinguish it from other inventions.

The subject of the present invention is an internal combustion engine of the rotary type which is provided with a stationary crank shaft and a plurality of cylinders which are adapted to rotate as a unit about such crank shaft. It is this type of engine which can be built to give a maximum horse power with a minimum of weight. To still further decrease the proportion of weight to horse power it is desirable to construct the engine of the 2-cycle type. The usual 2-cycle engine, whether of the two or three port type is notoriously inefficient, and to remedy this objection I have provided in the present engine simple but efficient means for completely scavenging the burnt gases from the cylinder and for admitting at the proper time a full charge of fresh gas. In addition to this feature I have provided a self starting means for the engine as well as other new and improved features to be hereinafter described. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

Figure 1 is a central section through my improved engine; Fig. 2 is an end elevation of the engine showing in side elevation the pump mechanism; Fig. 3 is a plan view showing the attachment of the muffler to the cylinders; and Fig. 4 is a section on the line 4-4, Fig. 1.

A stationary crank shaft 1 having a single off-set or throw 2 is fixed between two stationary members or plates 3 and 4 the crank shaft being engaged by three connect-

ing rods 5 each attached to a piston 6 the 55 pistons operating in cylinders 7. The engine is preferably formed with three cylinders, such three cylinders 7 being connected to a crank case 8 which is rotatably mounted upon the crank shaft 1. The number of 60 cylinders is of course immaterial, as three or more may be used, but as substantially continuous power can be obtained from three cylinders operating on the 2-cycle principle the preferred engine is thus built. 65

Each of the cylinders is provided with a plurality of exhaust ports 9 adapted to be uncovered upon the downward stroke of the pistons 6 the head 10 of each cylinder being formed with a lateral extension 11 in which 70 there is seated a puppet valve 12 normally closed by a spring 13, valve stems 14 being connected to the valves 12, and such stems 14 being adapted to be raised upon rotation of the cylinders as they strike against a 75 cam 15 attached to a sleeve 16 which is rotatably mounted upon the crank shaft 1 and is normally held in fixed relation thereto by means of a stop 17 on the sleeve engaging against a second stop 18 attached to one of 80 the plates 3 in which the crank shaft is fixed. The cam 15 is attached to the sleeve by means of a disk 19 which is mounted in a casing 20 attached to the cylinders and rotatable therewith, such casing 20 snugly 85 fitting about the sleeve 16 and the sleeve having slots or openings 21 at its inner end to permit passage of gas through a passage 22 formed in the crank shaft and opening laterally into the casing 20. In the inner 90 wall 23 of the casing are formed a plurality of ports 24, one for each cylinder, each port being connected to a valve chamber 25 in the adjacent cylinder by means of a conduit in the form of a small tube 26. The disk 19 is 95 provided with a single port 27 which is adapted to register successively with the ports 24 in the side 23 of the casing 20 upon rotation of the cylinders about the crank shaft. 100

The crank case 8 is rotatably mounted upon the crank shaft 1 at one end through the medium of a roller bearing 30 disposed between the crank shaft and a sleeve 31 attached to the crank case 8, such sleeve being 105 also rotatably mounted in the fixed plate 4 by means of a second roller bearing 32, thus providing a secure and firm bearing for that

end of the crank shaft and also for the crank case and rotating cylinders. The other side of the crank case is rotatably mounted on the crank shaft by a bearing 34. Attached 5 to the sleeve 31 is any suitable clutch such as a multiple disk clutch 36 (here shown) for the purpose of transmitting the power of the engine to any desired mechanism.

The sleeve 31 attached to the crank case 8 10 is provided with a gear 33, such gear being suitably connected, preferably by means of a silent chain 36, with a second gear 37 which is adapted to drive, through a connecting rod 38, a two cylinder horizontal pump, each cylinder 39 in such pump being provided with inlet and outlet valves 40 and 41 respectively, the inlet valves 40 being connected to a manifold 42 connected to a carbureter 43 and the outlet valves 41 being connected to a second manifold 44 leading to a pressure tank 45. The pump is designed to maintain a pressure of approximately fifty pounds in the tank, and valves 46 and 80 are disposed on each side of the tank, these valves being of the usual globe type.

The pressure tank 45 is connected by means of a suitable conduit 47 to the end of the crank shaft 1, thus permitting the pressure fluid to pass from the tank 45 to the casing 20 about the crank shaft and to thus supply the cylinders in turn with a proper amount of suitably mixed gas and air. Either gasolene, kerosene, or other fuel may be used in the carbureter, depending of course upon the particular construction of the same.

Each cylinder is provided with a spark plug 50 of the usual construction, such plug being connected to a terminal 51 fixed in an insulating disk 52 attached to the cylinders 7. Adjacent to such disk is a second disk 53 attached to the crank shaft 1, such disk 53 being also of insulating material and having a terminal 54 opposite to the terminal 51 in the first-named disk, the spark being adapted to jump between such two terminals upon the contact of terminals 55 and 56 mounted opposite to each other in such two disks 52 and 53 respectively and connected to the primary circuit of the usual magneto or batteries. The terminals in the disks will of course be so disposed that the spark will occur in the cylinder at the proper time to ignite the charge.

The cylinders are preferably of the air-cooled type, being provided with ribs 60 adapted to catch the air and provide for the radiation of the heat from the cylinders. 60 The exhaust ports 9 in each cylinder are spaced through approximately 120 degrees and are covered by a sleeve 61 connected to the inner casing or chamber 62 of a three-chamber muffler, such inner chamber being 65 provided with apertures 63 on all sides per-

mitting the gas to expand through the same into the second chamber 64, which is also provided with apertures 65 on all sides connecting with a third or outer chamber 66, the latter having apertures 67 only on the side opposite to the engine cylinders. Thus each cylinder discharges into the circular muffler, the gas being directed away from the engine as indicated. Other mufflers of suitable type may be used, if desired, but the present one is particularly adapted to the rotary construction and is hence preferred.

The crank shaft 1 is formed with a second internal passage 68 extending from one end through the offset portion, there being 70 leads 69 from such passage to the outside of the crank shaft. This passage may be connected with any suitable supply of lubricant, the various bearing surfaces being thus lubricated while the walls of the cylinders are 75 forced out through the connecting rods and is thrown to the walls of the cylinders. By using only three cylinders the connecting rods may be attached to the crank shaft as 80 shown, each having a generous bearing surface on the crank shaft. This is an important feature of the present construction, as much difficulty has been met with in the connecting rods and their bearing surfaces in 85 the usual rotary engine.

To start the engine it is only necessary to rotate a handle 70 attached to the sleeve 16 through one-half revolution. This operation raises one of the valve stems and opens 90 the valve and simultaneously connects the casing 20 with the passages leading to the valve chambers. In this way gas is admitted to each cylinder in turn, such gas being under approximately 50 pounds pressure, and being sufficient to start the rotation 95 of the cylinders and to start their firing. As soon as the rotation has begun the sleeve 16 is returned to its normal position by the friction of the casing 20 upon the same, thus 100 leaving the engine in the position shown in Fig. 1. The advantage of supplying the fuel under pressure is considerable as in this way the fresh fuel that is admitted to the cylinders can be used to force out the last remnants 105 of the burnt gas, this action being made possible by the use of the mechanically operated inlet valve timed to open at the same time that the exhaust port is uncovered 110 by the piston. It is important that a distributing valve, such as the disk 19 in the casing, be used, and this disk is so timed in relation to the inlet valves in the cylinders that gas is admitted to the valve chambers 115 simultaneously with the opening of the valve. In this way all pressure on the valve is removed, as if the gas were always in the valve chamber it might leak through the valve, thus causing an irregular operation of the engine and putting an undue strain upon 120 125 130

the springs which normally hold the valves closed.

The present engine when built in the three-cylinder form here shown, has been found to give a very high power output and to weigh but very little, thus adapting it particularly for use in aeroplanes, hydro-planes and the like, although its use is of course not limited to such installations, as it may also be used in automobiles, and in fact wherever a low weight is an important consideration.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In an internal combustion engine, the combination with a stationary crank shaft and a cylinder rotatable thereabout, said cylinder having an exhaust port controlled by a piston; of a high pressure storage tank, an independent pump operated by said engine and adapted to supply gaseous fuel at high pressure to said tank, connections from said tank to said cylinder, a mechanically operated inlet valve adapted to control the admission of such high pressure gaseous fuel to said cylinder, said valve being timed to admit such high pressure gaseous fuel to said cylinder upon the opening of such exhaust port, and manually operable means adapted to open said inlet valve to permit the admission of such high pressure gas to start said engine.

2. In an internal combustion engine, the combination with a cylinder provided with an exhaust port controlled by the piston, an inlet valve adapted to control the admission of high pressure gaseous fuel to said cylinder, a cam adapted, upon rotation of either said cam or said valve relative to the other, to open said valve, said cam being timed to admit such high pressure fuel upon the opening of such exhaust port, and manually operable means adapted to cause relative rotation of said cam and said valve thereby admitting high pressure gas to said cylinder to start said engine.

3. In an internal combustion engine, the combination with a cylinder provided with an exhaust port controlled by the piston, of a fluid pressure storage tank, an independent pump operated by said engine and adapted to supply gaseous fuel at high pressure to said tank, a cylindrical casing, connections from said tank and said cylinder to said casing, a mechanically operated inlet valve adapted to control said connection to said cylinder from said tank, and a second valve in said casing adapted to con-

trol the discharge of gas into said connection to said cylinder, said two valves being timed to operate in synchronism.

4. In an internal combustion engine, the combination with a cylinder provided with an exhaust port controlled by the piston, of a fluid pressure storage tank, an independent pump operated by said engine and adapted to supply gaseous fuel at high pressure to said tank, a cylindrical casing, connections from said tank and said cylinder to said casing, a mechanically operated inlet valve adapted to control said connection to said cylinder from said tank, and a second valve in said casing adapted to control the discharge of gas into said connection to said cylinder, said two valves being timed to operate in synchronism, and manually operable means adapted to synchronously open said two valves, thereby admitting gas at high pressure to said cylinder to start said engine.

5. In an internal combustion engine, the combination with a cylinder provided with an exhaust port controlled by the piston, of a fluid pressure storage tank, an independent pump operated by said engine and adapted to supply gaseous fuel at high pressure to said tank, a cylindrical casing, connections from said tank and said cylinder to said casing, a puppet valve adapted to control said connection to said cylinder from said casing, a cam adapted, upon relative rotation of said cam and said valve, to open said valve, and a second valve in said casing adapted to control the discharge of gas into said connection to said cylinder, upon relative rotation of said second valve and said casing.

6. In an internal combustion engine, the combination with a cylinder provided with an exhaust port controlled by the piston, of a fluid pressure storage tank, an independent pump operated by said engine and adapted to supply gaseous fuel at high pressure to said tank, a cylindrical casing, connections from said tank and said cylinder to said casing, a puppet valve adapted to control said connection to said cylinder from said casing, a cam adapted, upon relative rotation of said cam and said valve, to open said valve, a second valve in said casing adapted to control the discharge of gas into said connection to said cylinder, upon relative rotation of said second valve and said casing, and manually operable means adapted to cause relative rotation of said puppet valve and said cam and also of said second valve and said casing, thereby admitting high pressure gas to said cylinder to start said engine.

7. In an internal combustion engine, the combination with a fixed crank shaft, having a longitudinal passage therein, such passage having a lateral opening, a cylinder

rotatably mounted on said crank shaft, an exhaust port in said cylinder controlled by the piston, an inlet valve in said cylinder, a spring adapted to normally seat the same, 5 means adapted to supply gaseous fuel at high pressure to such passage in said crank shaft, a casing rotatably mounted on said crank shaft about the lateral opening of such passage and attached to said cylinder, 10 said casing being provided with a port, a normally closed conduit connecting such port to said inlet valve, and means adapted to synchronously open said inlet valve and said conduit, thereby admitting high pressure gaseous fuel to said cylinder. 15

8. In an internal combustion engine, the combination with a fixed crank shaft, having a longitudinal passage therein, such passage having a lateral opening, a cylinder 20 rotatably mounted on said crank shaft, an exhaust port in said cylinder controlled by the piston, an inlet valve in said cylinder, a spring adapted to normally seat the same, a casing rotatably mounted on said crank 25 shaft about the lateral opening of such passage and attached to said cylinder, said casing being provided with a port, a normally closed conduit connecting such port to said inlet valve, a disk attached to said crank 30 shaft in said casing, said disk having a port adapted, upon rotation of said casing and said cylinder, to register with such port in said casing, and a cam formed on the periphery of said disk, said valve having a 35 valve stem reciprocably mounted in said casing and adapted to be actuated by contact with said cam to open said inlet valve, such port in said disk being so disposed that it registers with such port in said casing simultaneously with the opening of said inlet valve by said cam. 40

9. In an internal combustion engine, the combination with a fixed crank shaft, having a longitudinal passage therein, such 45 passage having a lateral opening, a cylinder rotatably mounted on said crank shaft, an exhaust port in said cylinder controlled by the piston, an inlet valve in said cylinder, a spring adapted to normally seat the same, 50 a fluid pressure storage tank, an independent pump operated by said engine, and adapted to supply gaseous fuel under high pressure to said tank, a conduit connecting said tank to such passage in said crank shaft, 55 a casing rotatably mounted on said crank

shaft about the lateral opening of such passage and attached to said cylinder, said casing being provided with a port, a normally closed conduit connecting such port to said inlet valve, a disk attached to said crank 60 shaft in said casing, said disk having a port adapted, upon rotation of said casing and said cylinder, to register with such port in said casing, and a cam formed on the periphery of said disk, said valve having a 65 valve stem reciprocably mounted in said casing and adapted to be actuated by contact with said cam to open said inlet valve, such port in said disk being so disposed that it registers with such port in said 70 casing simultaneously with the opening of said inlet valve by said cam.

10. In an internal combustion engine, the combination with a fixed crank shaft, having a longitudinal passage therein, such passage having a lateral opening, a plurality of cylinders rotatably mounted on said crank shaft, exhaust ports in said cylinders controlled by the pistons, inlet valves in said cylinders, springs adapted to normally seat 80 the same, a fluid pressure storage tank, an independent pump operated by said engine, and adapted to supply gaseous fuel under high pressure to said tank, a conduit connecting said tank to said passage in said 85 crank shaft, a casing rotatably mounted on said crank shaft about the latter opening of such passage and attached to said cylinders, said casing being provided with a plurality of ports, normally closed conduits connecting such ports to said inlet valves, a disk attached to said crank shaft in said casing, said disk having a port adapted, upon rotation of said casing and said cylinder, to register successively with such ports in said 90 casing, and a cam formed on the periphery of said disk, said valves having valve stems reciprocably mounted in said casing and adapted to be actuated by contact with said cam to open said inlet valves, such port in 95 said disk being so disposed that it registers with such ports in said casing simultaneously with the opening of said inlet valves by said cam. 100

Signed by me, this 25th day of June, 1913.

ERNEST W. PRIGAN.
